United States Statutory Invention Registration Design

[19]

Kingsley

[11] Reg. Number:

H1295

[43] Published:

Apr. 5, 1994

[54] FISHERMAN'S PLIERS

[57]

CLAIM

[76] Inventor: Gerald E. Kingsley, P.O. Box 158, Lebanon, Oreg. 97355

The ornamental design for a fisherman's pliers, as shown and described.

1 Claim, 4 Drawing Sheets

[21] Appl. No.: 9,541

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.
